DESIGN FOR A SWIM SUIT

Margit Fellegi Laszlo, Los Angeles, Calif., assignor to Cole of California Inc., Los Angeles, Calif.

Application October 25, 1944, Serial No. 115,965

Term of patent 7 years

(Cl. D3—17)

To all whom it may concern:

Be it known that Margit Fellegi Laszlo, a citizen of the United States, residing at Los Angeles, in the county of Los Angeles and State of California, has invented a new, original, and ornamental Design for a Swim Suit, of which the following is a specification, reference being had to the accompanying drawing, forming a part thereof.

The figures in the drawing are, Fig. 1, a front elevational view; Fig. 2 a side elevational view and Fig. 3 a rear elevational view with the bra portion untied of a swim suit showing my new design.

I claim:

The ornamental design for a swim suit, as shown.

MARGIT FELLEGI LASZLO.
